UNITED STATES PATENT OFFICE.

JOHN C. TURNER, OF DAYTON, OHIO.

CONVERSELY-TURNING CAROUSEL.

1,377,641.

Specification of Letters Patent. Patented May 10, 1921.

Application filed June 7, 1917, Serial No. 173,324. Renewed October 5, 1920. Serial No. 414,831.

To all whom it may concern:

Be it known that I, JOHN C. TURNER, a citizen of the United States, and residing at Dayton, in the county of Montgomery and 5 State of Ohio, have invented a new and Improved Conversely-Turning Carousel, of which the following specification is a full disclosure.

This invention deals with gravity toys 10 and it proposes an arrangement in the nature of a carousel whereby suitable puppets or other toy-like imitations of conventional devices, such as trains, may be propelled continuously with a pleasing effect for a 15 short period.

One object is to provide a toy embodying a circular track and a central tower so connected and arranged as to automatically 20 propel a train in one direction on said track, and a portion of said tower or figures connected therewith in an opposite direction.

Another object is to devise a gravity toy 25 and to so arrange the parts that a weight in its descent will produce opposite movements in two different elements, thereby rendering a pleasing effect.

Other objects will be in part obvious from the annexed drawings and in part indicated in connection therewith by the following 30 analysis of this invention.

This invention accordingly consists in the features of construction, combination of parts, and in the unique relations of the members and in the relative proportioning 35 and disposition thereof; all as more completely outlined herein.

To enable others skilled in the art so fully 40 to comprehend the underlying features thereof that they may embody the same by the numerous modifications in structure and relation contemplated by this invention, drawings depicting a preferred form have 45 been annexed as a part of this disclosure, and in such drawings, like characters of reference denote corresponding parts throughout all the views, of which:—

Figure 1 is a plan of the circular trackway and tower. Fig. 2 is a side elevation thereof; Fig. 3 is a vertical section of the tower 50 revealing the operating means. Fig. 4 is a horizontal section through line 4—4 of Fig. 3. Fig. 5 is a vertical section of a modified tower construction, and Fig. 6 is a section through line 6—6 of Fig. 5.

55 Referring to the drawings, the structure embodies stationary elements including a

stationary circular track *a* rigidly connected by means of radial arms *C* with a stationary base *B* rigidly supporting a post *D*; a tower *E* extending downwardly and providing a 60 slideway *E'* and being provided, at its lower end, with a collar *8* which is centrally apertured so as to loosely fit on the parts passing therethrough. In the modified form shown by Fig. 5, the base *B'* is hollow and the post 65 *D'* is in the form of a tubular rod to the upper end of which is rigidly attached a depending slideway *E*². The purpose of the non-rotatable slides *E'* and *E*² is to serve as a guideway for weights *G* and *G'*, respectively; in the one case, the weight being provided with a pin *3* coöperating with the slide-way *E'* and, in the other case, the weight *G'* being provided with an aperture *3*^a coöperating with the slideway *E*². These weights 70 *G* and *G'* can thus move vertically or are restrained from rotating by the aforesaid parts. Encircling the posts *D* and *D'* are spirals *H* which are threaded to the weights *G* and *G'*, respectively, so that as said 75 weights move vertically, the spiral will be rotated.

The motion of the spiral in one direction, *i. e.*, clockwise, is imparted to a member *2* rotatably journaled on the posts *D* and *D'*, 80 respectively. To that end, the lower ends of the spirals terminate in collars *6* journaled on the posts *D* and *D'* respectively, said collars having pivots *7* carrying pawls *h* which engage ratchet wheels *9* rigidly secured to the 85 members *2*. By reason of this construction, the members *2* will be rotated when the weights *G* and *G'* descend by gravity. For the purpose of presenting a pleasing effect, the members *2* may support various 90 ornaments. For example, as shown by Fig. 3, a balcony *F* is rigidly secured to the member *2* by means of a member *1*, said balcony being provided with a circular rail *f* so that 95 said balcony will rotate relatively to the stationary tower *E*. In the form shown by Fig. 5, the balcony *F'* is connected to the rotatable member *2* by means of a part *1*^a and is provided with an upstanding tubular portion *f'* inclosing the actuating parts and configured to represent a tower. In this case the 100 tower rotates with the balcony.

Arranged on the trackway *a* is a train *K* which is caused to travel in a direction reverse to the rotation of the balcony by means 105 of an arm *K*³ which is rigidly connected to a collar *K*² journaled on the posts *D* and *D'*, 110

respectively. A bevel gear K' is rigidly carried by the collar K^2 and receives its motion from the rotating member 2 through the gear J pivoted to an extension D^2 rigid with the posts D and D' , respectively. A bevel gear 2^a rigid with the member 2 rotates the gear J and, as will be seen, causes the collar K^2 to rotate in a direction opposite to that of the balcony.

- 10 To enable the weight G to be restored to its initial position, it is, in the form shown by Fig. 3, provided with a handle 4 whereby it may be lifted. In the modification shown by Fig. 5, the lifter is in the form of a string 4^a which passes through a suitable hole in the base B' and extends upwardly through the bore of the tubular post D' and thence over suitable pulleys to engage the upper portion of the weight G' . This enables the weight 20 to be lifted by pulling the string 4^a .

Having thus set forth the nature of the invention, what I claim herein is:—

1. A toy comprising a base, a central tower, a substantially vertical helix rotatably sup-

ported within said tower, a balcony mounted 25 to be rotated by said helix, a rotatable sleeve, propelling connections between said helix and said sleeve, a supporting arm sustained by and movable with said sleeve, a circular track, a train propelled by said arm and 30 adapted to run on said track, and a suspended weight having sufficient potential energy to rotate said helix and thereby actuate the elements connected therewith.

2. A toy including a plurality of rotatable 35 elements, connections therebetween for causing said elements to rotate oppositely; and means comprising a helix and a vertically movable weight acting in its descent to impart rotary motion to one of said elements.

In witness whereof, I hereunto subscribe my name, as attested by the two subscribing witnesses.

JOHN C. TURNER.
